FIG-6

The drawings of my ornamental design annexed hereto comprise the following:

FIG. 1 is a perspective view of stilt footrest showing my new design;

FIG. 2 is a front view thereof;

FIG. 3 is a top view thereof;

FIG. 4 is a bottom view thereof;

FIG. 5 is a side view thereof;

FIG. 6 is a side view thereof.

The characteristic features of my design reside in the upright guard positioned at the inner extremity of the footrest and in the wide and split appearance of the footrest as shown in FIG. 3 and FIG. 4.

I claim:

The ornamental design for a stilt footrest, substantially as shown and described.
